UNITED STATES PATENT OFFICE.

WILLIAM HENRY HARRINGTON, OF HARTFORD, CONNECTICUT, ASSIGNOR TO THE ARROW ELECTRIC COMPANY, OF HARTFORD, CONNECTICUT, A CORPORATION OF CONNECTICUT.

DESIGN FOR AN ATTACHMENT PLUG.

Application filed December 2, 1921. Serial No. 519,527. Term of patent 14 years.

To all whom it may concern:

Be it known that I, WILLIAM HENRY HARRINGTON, a citizen of the United States of America, residing at Hartford, in the county of Hartford and State of Connecticut, have invented a new, original, and ornamental Design for Attachment Plug, of which the following is a specification, reference being had to the accompanying drawing, forming part thereof.

The figure is an elevation of an attachment plug embodying my new design.

I claim:

The ornamental design for an attachment plug, as shown.

In testimony whereof I have signed my name to this specification.

WILLIAM HENRY HARRINGTON.
